UNITED STATES PATENT OFFICE.

WILLIAM H. RICKER, OF CAMBRIDGE, MASSACHUSETTS.

HOT-AIR HEATING SYSTEM.

No. 811,089.

Specification of Letters Patent.

Patented Jan. 30, 1906.

Application filed August 5, 1905. Serial No. 272,811.

To all whom it may concern:

Be it known that I, WILLIAM H. RICKER, a citizen of the United States of America, and a resident of Cambridge, in the county of Middlesex and State of Massachusetts, have invented certain new and useful Improvements in Hot-Air Heating Systems, of which the following is a specification.

This invention relates to heating systems, and has for its object the production of a suitable furnace in which coal-dust and similar material may be effectively used.

The invention consists in certain novel features of construction and arrangement of parts, which will be readily understood by reference to the description of the drawings and to the claims to be hereinafter given.

Of the drawings, Figure 1 represents a central vertical section; and Fig. 2 represents a transverse section of the same, the cutting plane being on line 2 2 on Fig. 1 and looking in the direction of the arrow.

Similar characters designate like parts throughout the figures of the drawings.

In the drawings, 10 represents a front shell of a furnace provided with suitable doors 11 to secure access to the interior of the fire-pot and another door 12 giving access to the ash-pit 13. Above the ash-pit 13, on suitable supports 14, are mounted members 15, of fire-brick or other suitable material, forming a suitable floor to the fire-pot 16. Said members are separated at one or more points to form an opening 17. The upper surfaces of the members 15 are inclined downwardly, as shown at 18, toward these openings 17. In the center of the fire-pot is located a retort 19, of fire-brick or other suitable material, said retort being open at the top and having its side walls provided with a plurality of openings 20, passing therethrough and communicating with the fire-pot 16. The bottom of said retort 19 is provided with a screw conveyer 21, extending downwardly toward the rear of the furnace through a suitable tube 22 into a coal-pit 23, separated from the fire-pot by a wall 24.

The coal-pit 23 is supplied with coal by means of a screw conveyer 25. (Shown in Fig. 1.) Where a plurality of furnaces are used, this screw conveyer will extend from one to the other and convey coal to the various coal-pits. The screw 21 is provided with a beveled gear 26, meshing with a companion gear 27 on the shaft 28, provided with a squared end 29, by which the screw may be

operated to convey coal from the pit 23 to the retort 19. This retort is intended to be filled with coal-dust and fine coal to the top thereof, over the upper edge of which the coal-dust and fine coal will be dropped onto the floor of the fire-pot into a heap, as indicated in dotted lines in the drawings. The mass of coal-dust outside of the retort is intended to be ignited, and the heat from the same will act upon the combustible within the retort 19 and cause gas to be generated therein, which gas will pass through the plurality of holes 20 in the walls of said retort to assist in said combustion. To provide a further supply of gas, a pipe 30 is provided extending downward from the top of said furnace and zigzagging above the fire-pot to provide suitable heating-surface therefor and finally terminating at 31 in said retort. The oil that passes through this pipe will become thoroughly heated and be formed into gas, which will be ejected from the outlet 31 in the retort, from which it will pass through the openings 20 to still further assist in the combustion.

The side walls 32 of the fire-pot are made of fire-brick or other suitable material and are surrounded on all sides by hot-air passages 33, which communicate at the top of the furnace with the hot-air chamber 34.

Above the retort 19 and extending between the front and rear air-passages is an air-shaft 35, made of fire-brick or other suitable material. This shaft is provided with a plurality of holes 36, inclined downwardly toward the burning combustibles and adapted to afford a supply of heated air to assist in said combustion. The side walls 32 of said fire-pot are also provided with a plurality of holes 37, also downwardly inclined toward the material being burned. Above the fire-pot 19 is a boiler 38, extending from the front to the rear of said furnaces. This boiler may be of any suitable type and consist of an inlet 39 and outlet 40, between which are interposed suitable steam-chambers 41 and pipes 42. The pipes 42 pass through baffle-plates 43 and 44, which direct the heat from the fire upward through the spaces between the pipes 42 over the baffle-plate 44, downward, and then under the baffle-plate 43 to the chimney 45.

The air-passage 34 is provided with an inlet 46, which supplies the air thereto to be heated and which will pass downwardly by forced draft or otherwise through the air-passages 33 and through the various openings

into the fire-pot. The doors 11 are provided with any suitable slides 47, by which fresh air may be supplied to the fire when desired. These doors 11 are adapted for use only when 5 it is desired to secure access to the interior of the fire-pot by the removal of portions of the walls thereof to renew any part or repair the same.

In each of the openings 17 is provided a 10 revoluble member 48, the exterior surface of which is provided with a plurality of projections adapted to coöperate with roughened plates 49 on either side of said openings 17 to 15 grind the slag or ashes which may collect upon the floor of the fire-pot and cause it to be pulverized as it passes downward through the openings 17 into the ash-pit 13.

The openings 50 are adapted for use to stir the fire when necessary or for use to start the 20 same when desired.

This makes a very convenient form of heating apparatus which gives an intense heat and is adapted especially to burn coal-dust and other material ordinarily waste.

25 It is believed that the operation of the invention will be thoroughly understood without any further description.

Having thus described my invention, I claim—

30 1. In a heating system, the combination of a fire-pot, a central retort therein extending upwardly from the floor of said fire-pot into which it opens at the top and provided with means for emitting gas from the interior thereof through the side walls, and means for supplying said retort with a combustible capable 35 of generating gas.

2. In a heating system, the combination of a fire-pot, a central retort therein opening at

the top into said fire-pot and provided with a 40 plurality of perforations through the side walls thereof, and means for supplying said retort with combustibles.

3. In a heating system, the combination with a fire-pot having a solid floor inclined toward openings therein, of a retort interposed between said openings extending upwardly from the floor of said fire-pot and provided with means for emitting gas from the interior thereof through the side walls, and means 50 for introducing into said retort combustibles capable of generating gas.

4. In a heating system, the combination with a fire-pot having a solid floor inclined toward openings therein, of a retort interposed 55 between said openings extending upwardly from the floor of said fire-pot and provided with means for emitting gas from the interior thereof through the side walls, and means for supplying combustibles through the bottom of said retort.

5. In a heating system, the combination of a fire-pot provided with means for supplying air to said fire-pot through its side walls and having a solid floor inclined toward openings through which the ashes may be ejected, a central retort for said fire-pot provided with perforations in its side walls for the emission 65 of gas from the interior thereof, and means for supplying combustibles through the bottom of the retort.

Signed by me at Boston, Massachusetts, this 2d day of August, 1905.

WILLIAM H. RICKER.
